TRAILER BODY

John L. Sporich, 3007 N. 33rd St.,
Tacoma, Wash. 98407

Filed Sept. 9, 1971, Ser. No. 179,251

Term of patent 14 years

Int. Cl. D12—10

U.S. Cl. D12—102

Fig. 1

Fig. 2

Fig. 3

FIG. 1 is a side elevational view of a trailer body showing my new design; the opposite side being substantially a mirror image thereof;

FIG. 2 is a top plan view; and

FIG. 3 is a front elevational view thereof.

The broken lines shown in the drawing are for illustrative purposes only, and constitute no part of the claimed design.

I claim:

The ornamental design for a trailer body, as shown and described.
